CLAIM

The ornamental design for keying flat for a power tool, as shown and described.

DESCRIPTION

FIG. 1 is a first perspective view of a keying flat for a power tool according to a first embodiment.

FIG. 2 is a second perspective view of the keying flat for a power tool of FIG. 1.

FIG. 3 is a third perspective view of the keying flat for a power tool of FIG. 1.

FIG. 4 is a fourth perspective view of the keying flat for a power tool of FIG. 1.

FIG. 5 is a fifth perspective view of the keying flat for a power tool of FIG. 1; and,

FIG. 6 is a front view of the keying flat for a power tool of FIG. 1.

The broken lines are included for the purpose of illustrating portions of the keying flat for a power tool and form no part of the claimed design.
